PAPER FEEDER

Lesley R. Tufts, Cleveland, Ohio, assignor, by
mesne assignments, to The Cleveland Folding
Machine Company, Mentor Township, Ohio, a
corporation of Ohio

Application January 23, 1931, Serial No. 510,636

9 Claims. (Cl. 192—126)

This invention relates to improvements in paper feeders, that is to say machines for feeding sheets of paper to folding machines, printing machines or the like. The machine of the 5 present invention resembles in many respects that disclosed in Patent No. 1,704,207 to Andrew Olson, embodying certain improvements thereover.

One of the objects of the present invention is the provision of a friction clutch connection in 10 the power drive which shall be simple in form, subject to little wear and highly effective in operation, while capable of easy disengagement by automatic means in the event that the orderly feeding of sheets should be interrupted in some 15 manner.

Another object is the arrangement of the said clutch in such manner as to control the advance of the stack of sheets, in this case a pile, as well as to control the operation of the sheet feeder, so 20 that at such times there shall be no power connection to the pile raising mechanism to interfere with the manual actuation. In the case of the machine of the Olson patent, above referred to, the pile mechanism remains connected with 25 the power source when the sheet feed is interrupted by operation of the sheet detector. That machine comprises a means for manually disconnecting the power from this mechanism, but should the operator forget to use this disconnecting means and attempt to operate the mechanism manually, he will receive through his operating crank an unpleasant jerk. In the case 30 of the present machine such a condition is impossible for the reason that the pile mechanism is automatically disconnected from the power 35 source whenever the sheet feeder is disconnected.

Other objects and features of novelty will appear as I proceed with a description of that embodiment of the invention which, for the purposes of the present application, I have illustrated in the accompanying drawings, in which

Figure 1 is a partial side elevational view of a pile feeder arranged in operative relation with a folding machine.

Fig. 2 is a plan view of the same, partly in section upon the line 2—2 of Fig. 1.

Fig. 3 is a vertical transverse sectional view taken substantially on the line 3—3 of Fig. 2.

Fig. 4 is a fragmental elevational view on a larger scale illustrating the clutch and its disengaging means.

Fig. 5 is an elevational view at right angles to that of Fig. 4, partly in section upon the line 5—5 of the latter figure.

Fig. 6 is an elevational view of the pile mech-

anism viewed from the opposite side of the machine, and

Fig. 7 is a plan view of the same.

In the drawings a portion of the framework of a pile feeder is shown at 10 and a fragment of a folding machine framework at 11. The pile support is illustrated at 12, being movable up and down in suitable guides. At opposite ends of this support there are attached chains 13 which extend upwardly over sprockets 14 and carry on their extremities suitable counter-balancing weights 15. The sprockets 14 are mounted upon a shaft 16 near the opposite ends thereof. This shaft also carries a worm wheel 17 which meshes with a worm 18 on a shaft 19, to the opposite 70 end of which is attached a bevel gear 20. The shaft 19, as will be seen by reference to Fig. 2, is mounted intermediate its ends in a bearing carried by a bracket 21. This bracket also supports a bearing for one end of a short shaft 22 75 that has a second bearing in the frame member 10 of the machine and carries a bevel gear 23 which meshes with the gear 20.

Upon the shaft 22 outside of the machine frame there is a ratchet wheel 24 whose hub is 80 pinned to the shaft as indicated at 25 in Fig. 7. Loosely supported upon this same shaft between the ratchet wheel 24 and the frame of the machine is a rock lever 26. One arm of this lever is pivotally connected with a pitman 27, whose 85 opposite extremity is pivotally attached to a crank 28 fixed upon a shaft 29 to which further reference will be made later. The other arm of the rock lever 26 is of irregular shape and carries a pintle 30 upon which is oscillatably supported 90 the hub 31 of a pawl 32 that is adapted to cooperate with the ratchet wheel 24. The hub 31 also carries arms 33 and 34. The extremity of arm 33 has a double bevel which enables the arm to be swung past a spring-pressed detent 35 carried 95 upon the lever 26. A boss 36 on the lever stops the movement of the arm 33 in one direction. Its movement in the opposite direction is of course limited by the engagement of the pawl 32 with its ratchet. It will be obvious that as 100 the crank 28 turns the pitman 27 will be reciprocated and the lever 26 rocked back and forth upon the shaft 22 without doing any work, that is when the pawl 32 is in the position illustrated in Fig. 6.

A rock shaft 37 mounted in one wall of the machine frame carries an arm 38 upon which is mounted a feeler wheel 39 which is adapted to rest upon the top of the pile of sheets and to move with said pile. Outside the machine frame 110

there is loosely mounted upon the shaft 37 an arm 40, upon the end of which there is a cam follower 41 which runs upon the contour of a cam 42 mounted upon the shaft 29. Integral with the arm 40 there is an oppositely extending arm 43 which is engaged by a coil spring 44 in a small housing 45 that is rigidly supported upon the shaft 37. An adjusting screw 9, threaded in the top of the housing 45, and adapted to be held in adjusted position by a lock nut 8, bears against the top of arm 43, and by this means the angular position of the arm 40 with respect to the arm 38 may be regulated to a nicety. A trip lever 46 is mounted at 47 in a bracket 48 attached to the frame. At its upper end this lever carries a trip 49 which is adapted to engage the arm 34 when the lever 46 is thrown to the left away from its position illustrated in Fig. 6. Pins 50 and 51, threaded into bosses 52 and 53 respectively, serve as adjustable stops to limit the movements of the lever 46. On the lower end of that lever there is a projection 54 which is adapted to be engaged by a finger 55 on the arm 40. As the pile of sheets descends, the feeler 39 descends and permits the follower 41 to run upon the low spots of the cam 42. When this action proceeds far enough the finger 55 swings the lever 46 over to the left, bringing the trip 49 into position to engage the arm 34 on the next downward stroke of the latter. Such engagement swings the hub 31 upon the pintle 30 and forces the arm 33 over the detent 35, thereby snapping the pawl 32 into operative relation with the ratchet 24. On the next upward movement of the pawl therefore the ratchet will be given a rotative impulse which will be communicated through the shaft 22, bevel gears 23, 20, shaft 19, worm 18 and worm wheel 17 to shaft 16, upon which the sprockets 14 are mounted. The slight rotation thus transmitted to the shaft 16 will produce a small upward movement of the pile support 12, which will enable the pile to raise the feeler 39. The follower 41 in the meantime will have ridden onto the high part of the cam 42; whereby the finger 55 will have moved away from the projection 54, permitting the lever 46, which is overbalanced, to again assume by gravity the position illustrated in Fig. 6. Just prior to the end of the active stroke of the pawl 32 the arm 34 encounters an adjustable stop 7 which throws the pawl out of operative relation with the ratchet wheel and causes the arm 33 to ride over the detent 35, whereby the pawl is again held out of operative position until such time as the pile descends sufficiently to again cause the trip 49 to be brought into position to catch the arm 34 on a downward stroke of the latter. It will be understood that the stop 7 is so set and adjusted that it just clears the arm 34 when the pawl 32 is in the inoperative position illustrated in Fig. 6.

Referring again to Fig. 1, 60 is a belt by means of which power may be transmitted from a motor (not shown) to a pulley 61 on the folding machine. Rigidly attached to the pulley 61 are a pair of sheaves 62 and 63, each adapted to receive a V-belt 64 which runs over one of a second pair of sheaves 65 and 66. The latter sheaves are rigidly and preferably integrally connected together and with a clutch element 67 that is faced with friction inserts 68. These inserts normally engage one face of a clutch element 69 which consists of a circular plate or disk that is pinned to a shaft 70 which is capable of a slight longitudinal movement. The shaft 70 carries a feed roll 71. At its remote end it is rotatably mounted

in a bearing 72 for which there is a cover 73 that is secured to the frame of the machine by bolts or studs 74. In this cover there is threadably mounted an adjusting screw 75 which serves to move one abutment of a coil spring 76, the opposite end of the spring engaging the roll 71. The spring 76 therefore tends to move the shaft 70 endwise and to hold the clutch elements 67 and 69 in engagement. 80

The sheaves 65, 66 and clutch element 67, which are preferably integral, are freely rotatable upon the shaft 70. Their movement away from the clutch element 69 is prevented by a bracket 77. In other words the bracket 77 takes the reaction of spring 76 transmitted by shaft 71 through the two clutch elements, 69 and 67. Extending inwardly from one side of the bracket 77 there is a bearing boss 78 in which is mounted the shank of a bolt 79 that serves as a trunnion, its threaded end being screwed into a yoke 80 which is thereby supported by the trunnion so that it may partake of slight turning movements in its own plane. An adjusting screw 81, threadably mounted in the bracket 77, engages a projection 82 upon the rear of the yoke, whereby the latter may be tilted 95 to the extent desired. 100

The bracket 77 is provided with an extension 83. In bearings formed in this extension and in the frame 10, there is mounted a short shaft 84 to which is secured a crank 85. From the outer 105 end of this crank there is suspended by a pivotal connection a wedge 86 which is preferably faced with friction material 87 on its side toward the disk 69, this side of the wedge being vertical. The other side of the wedge is inclined, as indicated in Figs. 3 and 4, and is adapted to slide against the inclined upper end 88 of the yoke 80. On its lower end the wedge 86 has a foot 89 which is adapted to engage the lower end 90 of the yoke 80, whereby the downward movement of the wedge 115 is limited. On the shaft 84 inside the machine frame there is a crank 91 which is connected by a link 92 with a crank 93 on a shaft 94, the crank 93 having an extension or handle 95, by means of which the shaft 94 may be rocked through a 120 limited angle. By this system of links and levers the wedge 86 may be raised and lowered. Other means for rocking the shaft 94 will be described hereinafter. When the wedge 86 is pushed down sufficiently, it acts against the end 88 of the yoke 125 as an abutment to force the clutch element 69 away from the clutch element 67. Very little effort is required in order to accomplish this result, for the reason that as soon as the wedging effect is sufficient to cause intimate engagement 130 of the friction material 87 with the clutch plate 69, the rotation of the latter serves to carry down the wedge. 135

In the operation of the machine the shaft 94 is arranged to be rocked in order to bring about the descent of the wedge 86 and the disengagement of the clutch whenever more than a single sheet is fed at one time or whenever a sheet of unusual thickness is fed. To this end I employ a sheet detector, which may be the same or approximately 140 the same as that disclosed in the above mentioned patent to Olson. Sheet detectors or caliper devices of this kind are well-known in the art, and hence I have included no detailed disclosure of the same in the present case. Referring to Figs. 2 and 3, 96 is a square rod along which is 145 adjustable a bracket 97 that carries a vertically movable arm 98. This arm supports a horizontal pintle upon which is loosely rotatable a wheel 99 adapted to be driven by the roll 71. A second 150

wheel 100, supported on the same horizontal pin-
5 tle, is weighted on one side to maintain it in a certain position. The wheel 100 is adjusted to such a height that a single sheet of paper of proper thickness may travel over the roll 71 without rotating the wheel 100. Should two sheets be fed together however, or should a single sheet of excessive thickness pass between the roll 71 and the wheel 100, the latter will be rotated and a projection 101 upon the same will strike an arm 102 mounted upon the shaft 94, by means of which the latter will be rocked so as to depress wedge 86 through the linkage previously described. In this manner an interruption of the sheet feed is brought about before the double thickness of paper can cause any material trouble in the operation of the machine. After the machine has again been cleared, the operator may raise the wedge 86 by movement of the handle 95 in the direction of the arrow in Fig. 5, enabling the spring 76 to again cause the engagement of the clutch elements and the resumption of the feed. For the sake of convenience I have provided a further means for stopping or starting the feeding machine manually from the opposite side of the machine near the folding machine. For this purpose I employ a reciprocable rod 103 which extends from the folding machine forward to a crank 104 on a crank shaft mounted in the frame 10. On this same shaft there is another crank 105 which is connected by a link 106 with a crank 107 on the shaft 94. In order that there may be operation of the shaft 94, as for instance by means of the sheet detector, without affecting the link 106, the crank 104, 105 and the rod 103, the connection between the link 106 and the crank 107 is made by means of a pin and slot, providing lost motion, as illustrated particularly in Fig. 6.

The actual feeding of sheets is effected by a suction wheel 108 of well known form mounted upon a rotating shaft 109. On this shaft there is a gear 110 which is driven through idlers 111 and 112 from a gear 113 on shaft 70. The suction line leading to the wheel 108 is indicated at 114 in Figs. 1 and 2.

The gear 113 also meshes with a gear 115 on a shaft 116. On the opposite end of that shaft there is a further gear 117 which meshes with a gear 118 on the stub shaft 29 which carries cam 42, and by means of which that cam and the crank 28 are driven.

As each sheet leaves the feed roll 71 it travels onto a feed table 119 which is provided with spaced tapes 120 that are driven by a roller 121. At their opposite ends these tapes run over pulleys 122 which are mounted in adjustable brackets carried by the table. 123 is a metal plate in which is embodied the sheet registering means. This plate is provided with a series of holes in which may be loosely mounted balls 124 that are adapted to hold the sheets being fed in close engagement with the first tape 120 in order to insure good feeding engagement between the tapes and the sheets. Inasmuch as there is some tendency for the forward inner corners of the sheets to catch under one of the tapes 120 in travelling over the table, I cut grooves 125 in the top of the table parallel to and adjacent the several tapes, and I provide a deflecting plate 126 having an inclined portion extending into one of the grooves 125, this plate being supported from a rod 127 along the length of which it is movable, and the rod being mounted at one end in a bracket 128 which is adjustable lengthwise of a bar 129, the opposite end of the rod 127 being

supported upon a transverse bar 130. The plate 126 therefore may be caused to cooperate with any one of the grooves 125, and may be moved to any position along such groove. Hence it may always be brought to the proper location for a given width of sheet being fed. For a further description of this table construction reference may be had to my copending application Serial No. 422,718, filed January 23, 1930.

While I have disclosed herein an application of the invention to pile feeders specifically, it should be understood that the invention may be employed also upon continuous feeders, in which event mechanism for advancing the fanned-out bank of sheets would be substituted for the pile raising mechanism herein described.

In the operation of the machine, when from any cause the sheet detector wheel 100 is rotated, the arm 102 is moved through a portion of a revolution sufficient to produce a slight downward movement of the wedge 86. This downward movement is continued by a power impulse transmitted to the wedge by the clutch plate or disk 69, and the clutch elements 69 and 67 are therefore separated, whereupon the shaft 70 and the shafts 116, 29 and 109 cease to rotate. The suction feed is therefore stopped and the pile raising mechanism is disconnected, that is the cam 42 and the crank 28 both cease to turn. If the operator desires, he may now attach a crank to the pin on the end of shaft 22 and operate the same by hand, lowering the pile support 12 if that seems desirable. The power drive of the machine offers no obstacle to this manual operation of the pile support, because the power connections are broken by the disengaged clutch. This is a distinct advantage over earlier constructions wherein the pile mechanism remained connected with the power source when the sheet feed was interrupted. In that case, if the operator attempted to lower the pile manually, the pile feeler would immediately set the raising mechanism into operation and the operator would receive a sharp jerk through his hand-crank. As soon as the double thickness of paper or other obstruction is removed, the operator may throw the handle 95 to raise the wedge 86 and thus throw in the power to cause a resumption of the feeding, or if more convenient this may be brought about by actuation of the slidable rod 103.

It will be observed that when the clutch elements 67 and 69 are in engagement no appreciable wear will occur upon the friction inserts 68, while at the same time the drive is quite positive.

While in the foregoing description and in the accompanying drawings I have disclosed more or less in detail a certain embodiment of the invention, I desire it to be understood that such detail disclosure has been resorted to primarily for the purpose of fully illustrating the invention in accordance with the requirements of the statute, and is not to be construed as amounting to a limitation upon the scope of the invention.

Having thus described my invention, I claim:

1. In a paper handling machine, an endwise movable shaft having a clutch element fixed thereon, a second clutch element and a driving element secured together and loosely mounted on one end of the movable shaft, a fixed abutment for the second clutch element and the driving element, means for urging said shaft endwise to bring said clutch elements into driving relation, said means and said abutment preventing dis-

placement of the second clutch element and the driving element longitudinally of the shaft and means for separating said clutch elements.

5. 2. In a paper handling machine, an endwise movable shaft carrying a clutch element, a second clutch element and a driving element secured together and loosely mounted upon said shaft, resilient means for urging said shaft endwise to bring said clutch elements into driving relation, and common means for separating said clutch elements and applying braking power to said shaft.
10. 3. In a paper handling machine, an endwise movable shaft carrying a friction clutch element, a second friction clutch element loosely mounted upon the shaft, a driving element operatively connected with said second clutch element, means for applying pressure to said shaft normally in an endwise direction to hold said clutch elements in engaging relation, and means manually operable during rotation of the shaft for applying to the shaft a counteracting pressure in an opposite direction.
15. 4. In a paper handling machine, driven means to which sheets are fed, a feeder for feeding sheets thereto, means for advancing a quantity of sheets to the sheet feeder, a sheet detector, and means adapted to be operated thereby for disabling both said feeder and said advancing means while said

20. 30. first named means is being driven.
5. In a paper handling machine, driven means to which sheets are fed, a pile supporting platform, mechanism for raising the same, a sheet feeder adapted to feed sheets from the top of said pile to the driven means, a sheet detector, and means adapted to be set in motion thereby for disabling both said feeder and said mechanism while said first named means is being driven.

6. In a paper handling machine, driven means to which sheets are fed, a sheet feeder adapted

to feed sheets thereto, means for advancing a quantity of sheets to the sheet feeder, power connections from the driven means to said sheet feeder and advancing means, a sheet detector, and means adapted to be operated thereby for disabling said power connections while said first named means is being driven.

80. 7. In a paper handling machine, driven means to which sheets are fed, a sheet feeder adapted to feed sheets thereto, means for advancing a quantity of sheets to the sheet feeder, a driving motor, power connections between said motor and the driven means, power connections between the driven means and said sheet feeder and advancing means, said last-named connections comprising a clutch, a sheet detector, and means adapted to be operated thereby for disengaging said clutch.
85. 90. 8. In a paper handling machine, a pile support, and mechanism for raising said pile support automatically to maintain the top of the pile at a given level, a sheet detector, means adapted to be set in motion thereby for disabling said mechanism, and manual means operatively associated with said mechanism for raising or lowering said pile while the automatic operation thereof is interrupted through the intermediary of said detector.

95. 100. 9. In a paper handling machine, means for feeding sheets of paper, power connections for said feeding means, said connections comprising a clutch, and means automatically operated by a predetermined thickness of sheets for stopping said feed, said last named means comprising a wedge adapted to be brought into operative engagement with one of said clutch elements and a fixed abutment, whereby the rotation of the said element serves to transmit a power impulse to the wedge to further set the same and further separate said clutch elements.
